UNITED STATES PATENT OFFICE.

HOMER E. DUKE, OF MARKLEVILLE, AND GEORGE W. PIERCE, OF ANDERSON, INDIANA.

FILTERING APPARATUS.

Application filed March 17, 1922. Serial No. 544,548.

To all whom it may concern:

Be it known that we, HOMER E. DUKE and GEORGE W. PIERCE, citizens of the United States, and residents of Markleville and Anderson, respectively, county of Madison and State of Indiana, have invented a certain new and useful Filtering Apparatus; and we do hereby declare that the following is a full, clear, and exact description thereof, reference being had to the accompanying drawings, in which like numerals refer to like parts.

This invention relates to a means for filtering a liquid, and particularly is adapted to be associated with a pump and cistern for clarifying the water pumped from the cistern, and for purifying the same when desired.

The chief feature of the invention consists in the details of construction, whereby the device may be economically manufactured by preferably utilizing an ordinary drain tile; and another feature of the invention is the construction of the several parts of the device, whereby the same will be substantially similar to enable the same pattern to be utilized in the moulding of said parts.

The full nature of the invention will be understood from the accompanying drawings and the following description and claim.

In the drawings, Fig. 1 is a side elevational view of a water system showing the invention associated with a cistern and a pump. Fig. 2 is an enlarged central sectional view of the vacuum filter construction. Fig. 3 is a top plan view thereof. Fig. 4 is a transverse sectional view taken on the line 4—4 of Fig. 2 and in the direction of the arrows.

In the drawings 10 indicates a source of water supply, such as a cistern containing a supply of liquid 11. A pump 12, which is herein illustrated as a manually operable pump, is connected by the pipe 13 to the cistern, and said pipe 13 terminates beneath the level of the liquid or water 11. Herein the terminating end of the supply line 13 is provided with an enclosing partial vacuum filtering device, indicated generally by the numeral 14 in Fig. 1.

Reference will now be had to Figs. 2, 3 and 4, wherein the device indicated generally by the numeral 14 in Fig. 1 is illustrated in detail. In said figures there is

illustrated a top plate or head 15 and a bottom plate or head 16, said heads being substantially identical, with the exception of the central portion. The central portion of the bottom plate 16 is shown imperforate, as at 17, while the same portion in the top head or plate 15 is apertured to form a bearing 18. The bearing portion 18 receives the coupling 19, and said coupling is adapted to receive the threaded terminating end of the supply pipe 13 and the threaded end of a pipe extension 20, which extends from the top head 15 to the bottom head 16 and terminates adjacent the bottom head. With the foregoing construction it will be apparent that the same pattern from which the one head is cast or moulded may be utilized in the formation of the other head, in one instance the coupling 19 being inserted at the central portion and being cast integral. In order to form a union, the exterior surface of the coupling may be tinned or otherwise prepared, and when so prepared, a perfect weld is secured between the coupling 19 and the bearing or hub 18.

Since each of the heads 15 and 16 are similar, with the exception noted in the preceding paragraph, a further description of one will suffice for an understanding of the other. The head 15 is provided upon one face with an inwardly extending reinforcing flange 21, which flange herein is illustrated as tubular, and preferably annular and concentric with the annular boss 17 or 18. The head 15 adjacent the flange 21 is provided with a groove 22, and said groove is adapted to receive a gasket or sealing means 23. Another and herein concentric and inwardly extending flange 24 is provided, and said flanges 24 and 21 provide a groove or seat for the reception of a porous tubular member, herein illustrated as a cylindrical porous standard drain tile 25. The groove forming flange 24 is elongated, and, therefore, not only forms a guide or retainer for the cylindrical porous tile 25, but also provides a guide for a second and concentric porous standard drain tile 26. The head 15 adjacent the flange 24 is provided with a concentric groove or tile seat 27 which is adapted to receive a gasket or sealing means 28. The plate 15 upon its opposite face is provided with a reinforcing flange 29 which herein is illustrated as annular and is positioned opposite the flange 24, and intermediate the tile seats.

Upon the outer face of the head or plate and radiating from the hub 18 are a plurality of reenforcing radial ribs or fins 30, each of which terminates in a socket 31. The socket 31 is centrally apertured at 32, and herein said sockets are in spaced relation with each other about the periphery of the head, and said sockets are positioned at a greater distance from the center than 10 the groove 27.

It will be understood that a pair of concentric porous standard drain tiles 25 and 26 are positioned upon one of the heads 15 or 16 and the other head is then positioned 15 adjacent the other ends of said tiles, the several gaskets or sealing means having been previously applied to said heads. A plurality of tie rods or bolts 33 have their ends threaded, and said tie rods are adapted 20 to extend through registering openings 32 in the two heads. The nuts 34 engage the threaded ends of the tie rods 33 and are adapted to draw the ends together and serve to close the ends of the tubular and 25 porous tiles 26 and 25. It will be apparent that the rods 33 protect the outer tile 26 from casual injury.

If desired, the space between the two tubular members may be filled with a purifying agent or clarifying agent, or a mixture 30 of said agents. If the water is pure and odorless, the single tile 26 or 25 will be sufficient for efficient operation of the device. If the water is not odorless, charcoal may be 35 used between two or more of the concentric tiles, and said charcoal will remove the disagreeable odor or taste from said water. The porous tiles, of course, prevent the passage 40 of dirt, or other matters carried in suspension by the water. If the water is impure, the space between the two tiles 25 and 26 may be supplied with a chemical agent, which will purify the water in its 45 passage from one tile through the inner tile. The device is so constructed that the parts may be readily disassembled to provide access to the space between the tiles for renewing, when necessary, the several 50 agents or means in the space between said tiles.

The operation of the device is as follows: Water is supplied through the pump supply line 13 to the inner chamber 36 to prime the apparatus. The pump thereafter is operated and creates a partial vacuum in the 55 chamber 36. This partial vacuum, since nature abhors a vacuum of any degree, is filled by atmospheric pressure upon the water 11 in the cistern 10, which forces said water in said cistern through the tiles 26 and 25 into the chamber 36, in order to overcome the difference in pressure existing in the chamber 36 and atmospheric pressure. Thus, as long as the pump 12 is operated, there will be a removal of the water entering the chamber 60 36 from the cistern 10. When the pump has stopped operating, the water in the line 13 runs back into the chamber 36 and remains therein until the pressures are balanced. Subsequent operation of the pump 70 produces a partial vacuum in the chamber 36, as hereinbefore described, and the operation of the vacuum filter construction is 75 repeated.

The invention claimed is:

A pair of similar supporting heads for a filter construction formed from a pair of standard tubular drain tiles and a plurality of exteriorly positioned tile protecting and securing rods, each head including on 80 opposite faces axially projecting bosses, an annular reinforcement and centering ring projecting from one face and concentric with the boss, another and similar ring upon the opposite face and concentric with both 85 boss and first mentioned ring and of a larger diameter than either, a tile seat concentric with the boss and both rings and upon the same face as the first ring, and of a larger diameter than either ring, and 90 radial ribs extending from the boss through the second mentioned ring upon that face of the head and terminating in rod receiving apertured enlargements, the apertures extending through the head for rod reception. 95

In witness whereof we have hereunto affixed our signatures.

HOMER E. DUKE
GEORGE W. PIERCE.
